UNITED STATES PATENT OFFICE.

JOHN JOSEPH REVELEY HUMES, OF CAMBERWELL, COUNTY OF SURREY,
ENGLAND.

HYDROCARBURETED-AIR ENGINE.

SPECIFICATION forming part of Letters Patent No. 400,850, dated April 2, 1889.

Application filed March 8, 1887. Serial No. 230,098. (No model.) Patented in England September 4, 1886, No. 11,269; in Germany February 23, 1887, No. 21,510; in France March 3, 1887, No. 181,939; in Belgium March 5, 1887, No. 76,589; in Canada May 20, 1887, No. 44,330; in India August 27, 1887, No. 153; in Italy February 25, 1888, No. 3; in Spain May 10, 1888, No. 7,805, and in Ceylon May 24, 1888.

To all whom it may concern:

Be it known that I, JOHN JOSEPH REVELEY HUMES, engineer, a subject of the Queen of Great Britain and Ireland, residing at 18 Lillard Road, Camberwell, in the county of Surrey, England, have invented new and useful Improvements in and applicable to Hydrocarbureted-Air Engines, (for which patents have been granted in Great Britain, dated September 4, 1886, No. 11,269; in Germany, dated February 23, 1887, No. 21,510; in Italy February 25, 1888, No. 3; in France March 3, 1887, No. 181,939; in Belgium March 5, 1887, No. 76,589; in Spain May 10, 1888, No. 7,805; in Canada May 20, 1887, No. 44,330; in Ceylon May 24, 1888, and in British India August 27, 1887, No. 153,) of which the following is a specification.

This invention relates to motor-engines operated by the combustion of hydrocarbureted air, and particularly to such engines of this class as employ means for heating the charge of mixed air and vapor, and which have means for relieving the pressure in the cylinder at starting.

The novel features of my invention will be hereinafter fully described, and carefully defined in the claims.

And in order that the mode of carrying the invention into effect may be fully understood, I will proceed to describe the same with the aid of the accompanying drawings, wherein—

Figure 1 is a general sectional elevation of an engine embodying my improvements, and Fig. 1^a is an end view of the vapor-chamber O and appurtenances. Figs. 2 and 3 are detached and enlarged views illustrating certain features of the mechanism to be herein-after described. Fig. 4 is a view on a larger scale, showing the lamp for heating the gases in sectional elevation. Figs. 5 and 6 illustrate the reversing mechanism. Fig. 7 is an enlarged sectional view of the device for preventing back ignition of the mixed air and hydrocarbon vapor.

The form of engine represented in side elevation and part section in Fig. 1 is selected for the purpose of illustration as embodying

the various features of my invention or adapted for use therewith, the same being operated by the combustion of liquid hydrocarbon, in most respects as described in the specification to Letters Patent granted to me and dated October 5, 1886, No. 350,200.

A is the motor-cylinder, B the connecting-rod, C the crank, and D the crank-shaft. The latter is carried in bearings E, and is provided with a fly-wheel, F. Upon the crank-shaft D is secured a spur-pinion, G, which, through the intervention of a spur-wheel, H, drives the shaft J at half the speed of the crank-shaft. From the shaft J is operated a pump (of the usual kind and not shown in the drawings) for compressing air and delivering same by the pipe l to the reservoir M, in which the liquid hydrocarbon—assumed in the present instance to consist of petroleum—is stored. Air and petroleum respectively pass by way of the pipes m m' to the vaporizer N, and, having been mixed, enter the vapor-chamber O in the form of vapor or air permeated with liquid petroleum in a state of minute subdivision, the mixture being there heated by means hereinafter more fully described. An additional quantity of air is admitted to the vapor-chamber O, such air also being by preference heated, as herein-after explained. The combustible mixture passes from the vapor-chamber O through a device, P, (for preventing the inflammation extending back from the motor-cylinder t, the vapor-chamber,) and is drawn by way of the pipe p past a self-acting valve, a', into the motor-cylinder A, where, after being compressed, it is ignited by means of an electric spark or otherwise. In the valve-chamber a* there is also arranged an exhaust-valve, a², operated by means of the rod Q from an eccentric mounted on the shaft J.

The air-pump I employ is or may be precisely the same as that illustrated and described in my former patent, No. 350,200, and I have not deemed it necessary to illustrate it herein.

In starting hydrocarbureted-air engines in which the inflammable charge is compressed

previously to being fired the resistance to be overcome in turning the engine by hand is considerable, and increases with the size thereof. With a view to facilitating the starting of such engines, I provide means whereby a portion of the charge may be released from the motor or other compressing-cylinder while the piston is performing what in ordinary working would constitute its compressing stroke. Assuming this feature of my invention to be applied to an engine of the type hereinbefore described with reference to Fig. 1, I mount near the extremity of the reciprocating rod Q , operating the exhaust-valve lever, mechanism such as represented in Figs. 2 and 3, whereof the former is an end view of the motor-cylinder, while the latter shows the exhaust-valve lever and the mechanism for actuating the same from the rod Q in side elevation. In these figures, A is the motor-cylinder, a the valve-chest, while a' indicates the position of the inlet-valve and a^2 that of the exhaust-valve. v is a rocking lever, mounted by preference on an adjustable pivot, v' , and furnished at one extremity with an adjustable stop, v^2 , for the reciprocating rod Q to act against. The opposite extremity of the lever v engages with the spindle of the exhaust-valve a^2 , and serves to open the latter against the resistance of a spring. (Not shown in the drawings.)

The apparatus for enabling a portion of the charge to be released from the motor-cylinder while the engine is being started consists of a rocking lever, w , one arm of which bears against the exhaust-valve lever v and holds the valve open during the time that its opposite end is engaged behind a pin, x' , projecting laterally from a body, x , mounted upon the extremity of the rod Q . The body x is furnished with a weighted lever, x^2 , whereby it may be rotated a portion of a revolution. In the position represented in the drawings the pin x' is in gear with the lever w ; but when the handle x^2 is thrown over to the position indicated by the dotted lines the pin x' moves free of the lever w , the latter remaining inoperative. During the regular working of the engine the lever w occupies the position last referred to; but at starting it is subjected to the action of the rod Q , with the result that when the rod moves forward the exhaust-valve is opened, and as the rod approaches the end of its stroke in the opposite direction it engages with the lever w and again opens the exhaust-valve, the latter operation coinciding with the period during which compression of the charge would in ordinary working take place.

The device I have just described forms an automatic pressure-reliever for the engine, adapted to be utilized temporarily at any time, and fully under the control of the engineer.

The device hereinbefore referred to, and lettered P in Fig. 1, for preventing the inflammation incidental to the combustion of

the charge in a hydrocarbureted-air engine spreading from the cylinder or other chamber in which ignition takes place to the vessel whence the said charge is drawn, is illustrated in detail in Fig. 7, which is a longitudinal section of the device on a large scale, and it consists of a tube or passage filled with wires P' , of small diameter and disposed longitudinally. Under ordinary circumstances I find a passage of from fifteen to twenty centimeters in length completely charged with longitudinally-arranged wires of about one millimeter diameter adapted for the purpose. The gas or other inflammable fluid on its way to the explosion-chamber traverses the narrow interstices between the wires.

Devices for the prevention of back ignition constructed similar to that illustrated in Fig. 7 have before been employed in gas-engines, and I make no claim to the device herein. Their operation is too well known to require description.

In applying hydrocarbureted-air engines for actuating machinery or apparatus the action whereof requires to be frequently reversed, the stopping of the engine itself and the restarting thereof in the opposite direction of rotation are attended with considerable inconvenience. With a view to overcoming this objection I interpose between the crank-shaft of the engine and the shaft communicating the power to the machinery or apparatus driven means whereby the direction of rotation of the latter shaft (hereinafter termed the "first-motion shaft") may be reversed, while that appertaining to the crank-shaft of the engine in normal working is preserved.

For reversing the direction of rotation of the first-motion shaft when arranged in line with the crank-shaft, I employ means of the kind represented in Figs. 5 and 6, these being views taken at right angles to one another, the latter being partly in section. D is the engine-shaft or a shaft coupled thereto, the same revolving in one direction only. D' is a shaft in line therewith and required to be rotated in either direction. First, for rotating the shaft D' in the same direction as the shaft D , a friction or other coupling, d , is employed to connect the extremities of the two shafts. While the clutch is in gear the secondary shaft is driven direct; but upon the clutch being thrown out of gear by means of the hand-lever d' or otherwise the shaft D' becomes disengaged and inoperative, although the engine may continue in action. Secondly, for rotating the shaft D' in the reverse direction, the clutch d remains out of use, and a train of gearing is brought by means of the clutch d^2 (actuated by lever d^3) into operation. This mechanism comprises a subsidiary shaft, D^2 , mounted parallel with the main shaft, and furnished with two pinions, d^4 d^5 , one of these, d^4 , gearing with a spur-wheel, d^6 , formed on or attached to the freely-mounted members of the clutch d^2 on

the main shaft, while the other pinion, d^5 , engages with an internally-gearred toothed wheel, d^7 , freely mounted on the shaft D' , but capable of being coupled thereto through 5 a clutch, d^8 . If preferred, the spur-wheel d^6 and the internally-gearred wheel d^7 may be transposed. The striking gear and clutches are preferably arranged and operated in such a manner as primarily to disconnect 10 the shaft D' from the shaft D , and subsequently to bring into action the clutches d^2 and d^8 , whereby the motion of the shaft D is transmitted in a reverse direction to the shaft D' through the train of gearing $d^3 d^4 d^5$ 15 d^7 . Under such circumstances the shafts D and D' are entirely disconnected when the lever d is at mid-stroke. By suitably proportioning the train of gearing the speed of the shaft D' when running in the reverse direction may be less than, equal to, or greater 20 than that of the shaft D .

My improvements, specially applicable to hydrocarbureted-air engines of the class in which the fuel is supplied in a liquid state, 25 comprise means for heating the inflammable charge previously to its admission to the motor-cylinder or other combustion-chamber, the liquid, or a considerable portion thereof, being thereby volatilized and the subsequent 30 ignition of the mixture expedited and rendered more certain. With this object I apply to the vessel O , hereinbefore alluded to with reference to Fig. 1 as the "vapor-chamber," the heat derived from a lamp, R , or other convenient but independent heating apparatus, 35 or from the waste gases after escaping from the cylinder, or preferably from both these sources, the former being principally intended for use in starting the engine and the latter 40 for use during regular work.

The vapor-chamber O may be provided internally with a coil, S , or other heating pipes or passages, through which the waste gases are led from the exhaust-pipe s . The vapor- 45 chamber may also be furnished with a casing or jacket, S' , within which the heat from the lamp R circulates.

According to an alternative method of construction and working, the waste gases are 50 conveyed to the jacket and the heat from the lamp conducted through the internal coil, tubes, or passages; or the jacket of the vapor-chamber may be formed in two or more compartments, the waste gases traversing one or 55 more of such compartments, while the remaining compartment or compartments is or are reserved for the reception of the heated gases generated by the lamp; or the vapor-chamber may consist of two or more tubes or receptacles, one or more of such tubes being heated 60 from one of the sources described and the other or others from the other source, the vapor being caused to traverse both tubes or series of tubes, and thus to become heated, 65 whether the waste gases or the lamp be in operation for the purpose; or the vapor-chamber may be traversed by two tubes or series of

tubes or passages, one tube or series of tubes conveying the waste gases and the other tube or series of tubes the heat from the lamp. 70 After the exhaust or waste gases have been conducted through, around, or past the vapor-chamber, they may be conducted to another vessel traversed by a coil through which air is conveyed to the vaporizer or to the vapor- 75 chamber or to the motor-cylinder, according to the system of working employed.

The arrangement of apparatus represented in Fig. 1 is adapted for heating the air admitted to the vapor-chamber for mixing with 80 the hydrocarbureted air supplied to that chamber from the vaporizer N . The waste gases, after traversing the coil S , pass by way of the pipe t to the coil T , arranged within the air-chamber U , and finally escape by the pipe 85 t' . Air is drawn through the vessel U and passes by way of the pipe u to the vapor-chamber O .

Fig. 1^a is an end view of the vapor-chamber, showing the relative positions which the vaporizer N , outlet-pipe t for the waste gases, 90 and inlet-pipe u for hot air may assume.

Instead of the air to be heated being admitted to the vessel U and the hot gases passing through the coil T , it is obvious that the 95 hot gases may be admitted to the vessel, while the air is caused to traverse the coil. The construction of the air-heating apparatus may be varied in other ways without affecting the principles appertaining to this portion of my 100 invention.

Instead of conducting the waste gases to the vapor-chamber O , and thence to the air-vessel T , a portion of the waste gases may be applied for heating the vapor, while another 105 portion, or the remainder, may be conveyed to and through the air-heating vessel. By means of stop-cocks or throttle-valves the supply of gases for each of the purposes described may be varied and regulated. If preferred, 110 the air, before reaching the vaporizer, vapor-chamber, or motor-cylinder, may be heated by a lamp or other independent means, instead of by exposure to the heat conveyed by the 115 exhaust gases.

The lamp hereinbefore referred to for use in heating the combustible mixture contained in the vapor-chamber O , or for heating the air in the air-vessel T , may be of any known description adapted for burning methylated 120 spirit or other suitable inflammable fluid; or it may consist of a burner or series of burners connected with the vapor-chamber and supplied with hydrocarbureted air therefrom. In such a case it is expedient to provide the 125 passage from the vapor-chamber to the burner or burners with means such as hereinbefore described for preventing back ignition, and as shown in Fig. 7.

In some instances, instead of drawing from 130 the vapor-chamber the combustible fluid for supplying the burner or burners, I provide independent vaporizing apparatus for the purpose. Such a combined vaporizer and

lamp is represented in Fig. 4. V is a reservoir partially charged with liquid hydrocarbon, the portion of the reservoir above the liquid being supplied from the compressing-
5 pump attached to the engine with air at a pressure slightly above that of the atmosphere at an air-inlet, V². The top of the reservoir carries one or more mixing or vaporizing nozzles, which also serve as burners. Each
10 mixing nozzle or burner consists of a hollow body, v, whereof the upper end is closed with a cap, v', provided with a small orifice surrounding or immediately opposite the extremity of a tube, v². This tube is mounted
15 in the perforated diaphragm v³, and extends downward into the liquid contained in the reservoir V. Under the influence of the pressure to which the reservoir is subjected the liquid hydrocarbon is forced up the tube
20 v², while air passes up the interior of the body v through the perforated diaphragm v³ and meets the liquid issuing from the upper extremity of the tube v², the two fluids becoming thoroughly mixed as they escape together through the orifice in the cap v'. The inflammable mixture thus formed possesses when ignited considerable heating power.

The reservoir V may, if preferred, be provided with special means for generating the
30 requisite air-pressure, such means being adapted for manual operation or otherwise independently of the working of the engine. Such provision is convenient for use in heating the inflammable vapor previously to
35 starting the engine.

It will be understood from the foregoing description that my invention does not relate to that class of so-called gas-engines wherein the vapor of the hydrocarbon is generated by
40 heat applied to a vessel containing the liquid hydrocarbon. I do not heat the vessel or reservoir containing the liquid, but produce the vapor by mechanical means. I heat the vapor after it has been produced, as I have
45 already clearly explained.

What I claim as my invention, and desire to secure by Letters Patent, is—

1. The combination, in a hydrocarbureted-air engine, of the exhaust-valve of the motor-
50 cylinder, the rod Q, and intermediate lever, v, for actuating said valve at or near the end of the outstroke of said rod, and a pressure-reliever comprising the rocking lever w, one

end of which takes under the said intermediate lever, and a movable body or sleeve, x, on the rod Q, said body having a projecting part, as x', adapted to be moved into and out of engagement with the other arm of lever w, substantially as set forth.

2. In a hydrocarbureted-air engine, the combination, with the reservoir M, containing compressed air and liquid hydrocarbon, of a mechanical vaporizer, N, pipes m m, which lead the air and liquid hydrocarbon, respectively, to said vaporizer, and a vapor-chamber connected with the vaporizer N, said chamber being provided with appliances for utilizing the heat of the waste gases for heating its contents, and also with a lamp for heating the contents of said chamber before the engine is started, as set forth.

3. The vapor-chamber Q, provided with an exteriorly-arranged jacket, S', open at its lower side to receive the heated gases from a lamp or like exterior heater, and also provided with an internally-arranged conduit for the passage of the waste gases from the engine, substantially as set forth.

4. In a hydrocarbureted-air engine, the combination, with the reservoir M, for containing compressed air and liquid hydrocarbon, the mechanical vaporizer, and the pipes for leading the air and liquid hydrocarbon to said vaporizer, of the vapor-chamber connected with said vaporizer, the air-chamber U, connected with said vapor-chamber, and conduits for the heated gases, arranged within said vapor and air chambers, said conduits being connected to form a continuous passage for said gases, substantially as set forth.

5. The combination, with the main shaft D and the auxiliary shaft D', aligned therewith, of the internal gear-wheel, d', loose on shaft D' and provided with one member of a double clutch, the gear-wheel d⁶, fixed on shaft D, the pinion-shaft D², the pinions d⁴ and d⁵ on said shaft, meshing, respectively, with wheels d⁶ and d⁷, the member of the double clutch on shaft D, and the sliding member of said clutch on shaft D', substantially as set forth, whereby shaft D' may be driven in either direction by the shaft D.
